WIND ACTUATED ADVERTISING SIGN

Marcus P. Exline and William F. Beale, Dallas, Tex., assignors of one-third to Lily Morgan Lowrie, Houston, Tex.; one-third to Katherine Morgan Exline, Dallas, Tex.; and one-third to said Beale

Application January 2, 1937, Serial No. 118,757

5 Claims. (Cl. 40—125)

This invention relates to advertising devices and it has particular reference to wind propelled signs.

The principal object of the invention is to provide an animated advertising sign having a major element capable of rotating movement on a diametrical axis for adjustment to changes in wind direction and a plurality of minor elements each rotatable on a central axis and grouped about 10 said major element for collective operation as an attraction.

Another object of the invention is to provide an advertising sign of the character specified, in which said minor elements are preferably 15 coated with aluminum or luminous paint, in order to obtain a scintillating effect at night when light reflections are caught thereby, hence to attract the attention of passersby to the advertising matter carried by the central portion of the 20 major element.

With the foregoing objects as paramount, the invention has other and lesser objects, as well as certain salient features of construction, to become manifest as the description proceeds, 25 taken in connection with the accompanying drawing, wherein:

Figure 1 is a front elevation of the invention.

Figure 2 is a fragmentary detail view in perspective of one of the frames supporting a minor 30 element.

Figure 3 is a detail front elevation of the inner point of securement of the radial arms constituting the frames shown in Figure 2 and reinforcing members, and

35 Figure 4 is a side elevation of one of the minor elements of the assembly.

Continuing with a more detailed description of the drawing, reference is primarily made to Figure 1 in which the reference numeral designates a circular frame, mounted rigidly on a post or standard 2, suitably anchored in the ground or pavement. Within this frame is a similarly shaped member 3, having pivots 4, diametrically opposed to afford an axis through the 40 vertical plane of the said member 3. Within this member 3 is a still smaller ring 5, to which is welded or otherwise suitably secured the inner ends of a series of radially disposed reinforcing rods 6, as well as the inner ends of a similar 45 series of frames 7, arranged alternately with the rods 6, as shown.

In the center of the circular member 3 is disposed a pair of discs 8, arranged back to back and between which the structure shown in Figure 3 is interposed so that it might be concealed

by these discs. Suitable or desirable advertising copy 9 is intended to be carried by the discs 8, which may be made interchangeable or replaceable if the occasion so requires.

The centrally pivoted and therefore rotatable element 3, which is herein referred to as the major element of the assembly is caused to follow the direction of the wind, as a vane or the like. In being thus displaced, the series of minor elements or wind wheels 10 are always facing the direction from which the wind travels and are accordingly always in motion.

The minor elements 10, of course, may be of any design or shape to suit their requirements or the conditions under which they operate. They are mounted upon ferrules or tubular members 11, the latter receiving a pin 12 which is rigid with the members 11. The ends of this pin enter apertures 13 in the frame member 7, which, 20 obviously, is comprised of a strip of material, bent to define an area to receive the rotary element 10 and to provide parallel ends, lying against each other as a means of securement to the inner ring 5 and for rigid securement to the outer ring 3.

From the foregoing it is immediately apparent that the sign, properly mounted will be stationary but that the major element will rotate on its vertical axis with the wind and that the minor elements, regardless of the position of the major element, will rotate constantly when there is sufficient wind to effect their operation, it being understood that very little air movement is necessary to start and maintain the elements 10 in operation.

Manifestly, the construction as shown and described is capable of some modification and such modification as may be construed within the scope and meaning of the appended claims is also considered to be within the spirit and intent of the invention.

What is claimed is:

1. A wind actuated advertising sign comprising a stationary frame, a conforming rotary frame mounted in said stationary frame for rotation about a vertical axis carrying plates bearing advertising media and a series of wind wheels having relatively parallel axes radially disposed about and within the confines of said rotary frame about said plates.

2. A wind actuated sign comprising a standard, a stationary open frame mounted on said standard, a rotary frame mounted in said open frame on a vertical axis for rotation, plates disposed in said rotary frame and a plurality of wind wheels

having relatively parallel axes and arranged in said rotary frame about said plates for independent rotation.

3. An advertising sign comprising a body mounted for rotation on a vertical axis and a series of independently rotatable wind wheels mounted on relatively parallel axes and arranged radially in said body about its center and means on said body spaced inwardly from said wind wheels to receive advertising matter.

4. An advertising sign comprising a stationary open frame having a rotatable frame mounted therein on a diametrical axis and a series of flutter mills arranged in spaced relationship in said rotatable frame about its central point for independent rotation on relatively parallel axes, and a sign receiving means carried by said rotat-

able frame and spaced inwardly from said flutter mills.

5. An advertising apparatus comprising a stationary, open frame, a rotatable frame having a plurality of radially disposed arms embraced at their ends by a circular element, the latter being pivoted at diametrically opposed points in said frame, plates for the reception of advertising media affixed centrally to and on either side of said member and a series of independently mounted and rotatable wind actuated elements arranged in said member in spaced relation about said plates and rotatable on relatively parallel axes.
